UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPE-WRITING MACHINE.

1,071,439.

Specification of Letters Patent. Patented Aug. 26, 1913.

Application filed May 3, 1913. Serial No. 765,223.

To all whom it may concern:

Be it known that I, ALFRED G. F. KUROWSKI, a citizen of the United States, residing in the borough of Brooklyn, in the county 5 of Kings and State of New York, have invented certain new and useful Improvements in Type-Writing Machines, of which the following is a specification.

My invention relates to an improved 10 roller bearing mechanism for the paper carriage of a typewriting machine.

An object of the invention is to provide 15 an improved form and arrangement of bearing mechanism which will maintain accurate alinement and guiding of the carriage and prevent jumping or displacement of the carriage due to the shifting of the platen, or from other causes.

The carriage is supported at the front by 20 a roller running on a stationary guide rail and at the rear by two sets of bearing rollers, one located behind the platen, and the other below and somewhat to the rear of the platen axle. The two sets of rollers run in 25 ways comprising bearing surfaces formed on an inclined frame connected to the carriage frame, and opposite surfaces formed on stationary guide rails on the machine frame. The two sets of rollers are mounted 30 in a light frame or carrier which maintains the proper relation of the rollers, and the position of said carrier relative to the bearing surfaces is controlled by means of a pinion on the carrier meshing with racks secured respectively to the machine frame and 35 the bearing frame on the carriage. The bearing rollers are arranged in pairs, one roller of each pair having its axis perpendicular to the other roller. The rollers and their 40 bearing surfaces at the rear of the platen are arranged to prevent any substantial play of the carriage either vertically or in a horizontal direction. The weight of the paper carriage and the parts supported thereby 45 comes principally upon the rollers beneath the platen, the front and rear rollers serving to maintain the horizontal position of the carriage and prevent any tilting thereof about the lower rollers as a fulcrum.

50 Other objects and advantages will herein-after appear.

In the accompanying drawings, Figure 1 is a sectional elevation view of my invention applied to an Underwood typewriting machine. Fig. 2 is a sectional view as indi-

cated by the line $x-x$ on Fig. 1. Fig. 3 is a fragmentary view showing the bearing rollers and their carrier.

A rotary platen 1 is journaled in a platen frame 2 mounted for vertical movement in 60 the carriage frame 3, the platen frame being supported on swinging arms 4 pivoted at 5 to the carriage frame. The carriage is adapted to be driven by means of a spring drum in the direction of the platen axle, 65 said movement being controlled by a rack 6 on the carriage meshing with an escapement pinion 7 controlled by the usual escapement mechanism.

At the front of the frame 3 is a roller 8 70 which runs on a stationary carriage rail 9 on the machine frame 10. At the rear of the carriage frame is a set of bearing rollers arranged in pairs, each pair comprising rollers 11 and 12, the rollers 11 being substantially perpendicular to the rollers 12. Beneath the platen and somewhat to the rear of the platen axle is a similar set of rollers comprising pairs of rollers 13 and 14 perpendicular to each other. The rollers 80 are adapted to run on a rectangular bearing frame 15 rigidly secured to the paper carriage and comprising upper and lower guide rails 16 and 17 respectively, connected by pins 18.

Each of the rails 16 and 17 is substantially in the form of an angle iron, providing bearing surfaces at right angles to each other for the bearing rollers. The upper rail 16 thus forms bearing surfaces 19 and 20 for the rollers 12 and 11 respectively. The lower rail 17 likewise provides bearing surfaces 21 and 22 for the rollers 14 and 13 respectively. Opposite these bearing surfaces are corresponding surfaces formed on stationary guide rails 23 and 24, fixed to or forming part of the machine frame. The lower guide rail 23 thus provides bearing surfaces 25 and 26 parallel respectively with the surfaces 22 and 21. The upper rail 24 provides bearing surfaces 27 and 28 parallel with the surfaces 19 and 20 respectively.

The bearing rollers are held in proper relation by means of a light frame or carrier comprising longitudinal bars 29 connected by a central cross bar 30. This carrier is preferably made from a single piece of sheet material and comprises ears 31 bent up to form bearings in which the roller pivot pins 105 110

32 are secured. The rollers are prevented from creeping or displacement in the direction of the carriage travel by means of a pinion 33 connected to said carrier and meshing with racks 34 and 35 secured respectively to the machine frame and the frame 15 on the carriage. The pinion 33 is journaled on a shouldered screw 36 threaded into the cross bar 30 of the carrier. The 10 rack 34 may be adjustably connected to the rail 24 by screws 37 engaging the bifurcated ends of the rack.

It will be observed that the bearing frame 15 is inclined at an angle of about forty-five 15 degrees to the vertical, and is so positioned that the upper rollers 11 and 12 are behind the platen and approximately in the horizontal plane of the platen axle, while the lower rollers 13 and 14 are approximately 20 in the vertical plane of said axle. It will further be noted that the rollers 11 are not parallel with the frame 15, but are more nearly vertical, and the rollers 12 approximate a horizontal position. The bearing 25 surface 28 for the rollers 11 also approaches the horizontal position, and is approximately parallel to a plane passing through the front rollers 8 and the rear rollers 11. As a result of this arrangement, any tendency 30 of the rear end of the carriage to be lifted vertically, or of the carriage to be tilted about its bearing 8 as a fulcrum, is prevented by the bearing surface 28 which is directly opposed to such movement. Any 35 tendency also of the carriage to be shifted either forwardly or rearwardly is likewise squarely opposed by the approximately perpendicular bearing surfaces 19 and 27. Also the axes of the lower rollers 13 and 14 are 40 not normal to the plane of the frame 15, the rollers 13 approaching a horizontal position and the rollers 14 a vertical position. The rollers 14 carry most of the weight of 45 the paper carriage, and it is desirable that the bearing surfaces 21 and 26 should be approximately horizontal, so that the weight on the bearing surfaces will be more direct. The bearing surfaces 22 and 25, being approximately vertical, are in position to effectively oppose any play of the carriage in 50 a forward or rearward direction.

It will thus be seen that all of the roller bearings and their bearing surfaces are so arranged and disposed that they will co-operate to effectively prevent any material play of the carriage either in a vertical or horizontal direction, and also to prevent any tilting of the carriage. It is also found that by arranging the rollers and their bearing 55 surfaces substantially normal to, rather than at a considerable angle to the directions in

which pressure thereon is applied, friction, wear, and lost motion are reduced, and a smoother running of the carriage is secured.

Variations may be resorted to within the 65 scope of the invention, and portions of the improvements may be used without others.

Having thus described my invention, I claim:

1. In a typewriting machine, the combination with a traveling carriage, of an inclined bearing frame secured thereto having bearing surfaces in rear of and below the platen respectively, bearing rollers interposed between said frame and the machine 75 frame, and means for supporting and guiding the front of the carriage.

2. In a typewriting machine, the combination with a traveling carriage and a platen mounted thereon, of supporting 80 means for the carriage in front of the platen, bearing rollers in rear of the platen, bearing rollers beneath the platen, and ways for said rollers formed by bearing surfaces on the carriage and the machine frame re- 85 spectively.

3. In a typewriting machine, the combination with a traveling carriage, of a platen thereon, bearing roller in front of the platen, bearing rollers in rear of the 90 platen, the axes of said last-named rollers being substantially parallel with a plane passing through said front and rear rollers, and ways for said rear rollers comprising bearing surfaces parallel with said axes. 95

4. In a typewriting machine, the combination with a traveling carriage and a platen thereon, of bearing rollers, an inclined carrier supporting said rollers, the axes of said rollers being inclined to the 100 plane of said carrier, and bearings for said rollers.

5. In a typewriting machine, the combination with a carriage and a platen, of an inclined roller bearing frame secured to the 105 carriage, rollers running on said frame, stationary rails forming with said frame ways for the rollers, and means for supporting and guiding the front of the carriage.

6. In a typewriting machine, the combination with a carriage and a platen thereon, of an inclined roller bearing frame on the carriage in rear of the platen axle, bearing rollers interposed between said frame and the machine frame, and means in front of 115 the platen for supporting and guiding the front of the carriage.

ALFRED G. F. KUROWSKI.
